UNITED STATES PATENT OFFICE.

JOSEPH MCKAY, OF TROY, NEW YORK.

STARCHING-MACHINE.

SPECIFICATION forming part of Letters Patent No. 471,720, dated March 29, 1892.

Application filed August 27, 1891. Serial No. 403,902. (No model.)

To all whom it may concern:

Be it known that I, JOSEPH MCKAY, of the city of Troy, county of Rensselaer, State of New York, have invented new and useful Improvements in Starching-Machines, of which the following is a specification.

My invention relates to improvements in starching-machines, and more particularly to an improved arrangement of the conveying-belts used therein for passing the articles to be starched through and from out of the machines, and also to other features of construction having for their object the better adaptation of this class of machines to the uses for which they are designed.

My improvements upon this class of apparatus are shown as applied to the starching-machine described and illustrated in an application for Letters Patent made by me and filed January 27, 1891, Serial No. 379,349, and which is now pending.

Accompanying this specification, to form a part of it, there are five plates of drawings containing twelve figures illustrating my invention, with the same designation of parts by letter reference used in all of them.

In the illustrations, Figure 1 is a side elevation of the mechanism. Fig. 2 is another elevation taken on the side that is opposite to that shown at Fig. 1. Fig. 3 is an elevation of the front end of the machine and that end at which the articles to be starched are entered. Fig. 4 is an elevation of the rear end of the machine at which the starched articles are discharged. Fig. 5 is a vertical section taken on the line $x'x'$ of Fig. 4, and Fig. 6 is a top view of the machine. Fig. 7 is a perspective of one of the bearing-arms in which the journaled ends of one of the belt-conveying rollers turn and shown as detached from the machine. Fig. 8 is a section of one of the conveying-belt rollers, shown as detached and as taken on the line x^2x^2 of Fig. 5. Fig. 9 is a side elevation of a part of the machine, illustrating a modification by which the feed-rollers run continuously. Fig. 10 is a perspective of one of the cross-heads. Fig. 11 is a perspective of one of the slide-blocks of the cross-head, and Fig. 12 is a perspective of one of the center carriers and part of its cover.

The several parts of the mechanism thus illustrated are designated by letter reference,

and the function of the parts is described as follows:

The letter F designates the frames of the machine, within and upon which the working parts are connected and supported, and the letters f^2 designate a rearward extension of these frame parts at the rear end and at each side of the machine.

The letter T designates a trough adapted to contain liquid starch.

The letter t^2 designates a discharge-pipe from which the starch is drawn off when the machine has stopped running and is to be cleaned.

The letter G designates a steam-chamber that is arranged immediately beneath the starch-trough T for the reception of steam to keep the starch in the trough hot or warm, and this steam-chamber G is tapped at t^3 for the connection of a steam-pipe for the admission of steam, and at the other end it is shown as tapped for the insertion of a drip-cock for the escape of the water condensing from the steam.

The letter P designates a platform that is arranged within the starch-trough T, and this platform is made with a flat center part p^2 , that rises on an incline toward the rear, and the end parts p^3 and p^4 , that rise on an incline from said center part toward the top of the trough. The function of this platform is that of a support for and to take the strain from off the conveying-belts when pressed upon by the starching-rollers, as will be subsequently described herein.

The letter R' designates a belt-roller that is arranged to be within the starch-trough and made with bearings that are adjustable in a direction toward the ends of the trough, one of them being shown at Fig. 7 as separated from the machine. These bearings for the shaft-journals of the belt-roller R' are constructed upon the inner ends of arms A, of which there is one at each side of the machine, which at their outer ends are adjustably connected to the machine-frame and therefrom extended downwardly into the starch-trough at the front end of the machine, so as to be adjacent to the side walls of the starch-trough therewith. Each of these arms A is made with a bearing a^2 upon its inner end to receive one of the journals of the roller R', and

these bearings a^2 are preferably made with hinged bearing parts a^3 , connected by set-screws i to the other portion of the bearings. One of these arms A is shown as detached at Fig. 7 and with the hinged bearing-boxes as open.

The letter a^4 designates a slot that is vertically formed in the outer ends of each of these arms A, and a^5 pins that are upwardly projected from the top a^6 of the frame on which the outer ends of each of these arms rest, with the said pins projected upwardly through said slot at each side of the machine, and where projecting through the slot beyond the top of the frame a^6 each of these pins is provided with a head a^7 , that projects over the slot, so as to overlap its sides, so that said pins act as guides for the movement of the arms A.

The letter a^8 designates a set-screw that is threaded into the downwardly-projected end of each of the arms A, with the inner end of each of said set-screws, when screwed in, engaging with the downwardly-extended end part of the frame-top a^6 , on which the outer ends of arms A rest. As thus constructed and arranged, when the set-screws a^8 are screwed in the arms A, together with the connected roller R', are drawn outwardly, so as to increase the tension of the conveying-belt running on said roller R'.

The letter R² designates another belt-roller that is located at the rear end of the machine, which roller is provided with bearings g', as shown at Figs. 1 and 5.

The letter R³ designates a belt-roller that is smaller than the rollers R' and R² and is located adjacent to and back of the latter. This roller R³ is provided with bearings in boxes e', arranged to slide horizontally at each side of the machine. These bearing-boxes are operated in slides e², provided with a spring e³, arranged between each of said bearing-boxes e' and a spring-block e⁴, and the letter e⁵ designates a set-screw that is threaded into the plate e⁶, so that when the set-screws e⁵ at each side are screwed in they engage with the spring-blocks e⁴ and actuate the springs to crowd the bearing-boxes frontwardly and force the roller R³ closer to the roller R².

The letter R⁴ designates a belt-roller having bearings for its journals at b² at each side of the machine, these bearings being secured to a plate b³, with the latter adjustably secured to the side frame-extensions f³ of the frame at the top thereof.

The letter b⁴ designates a slot made vertically in each of the plates b³, and b⁵ designate pins that are upwardly projected from the top edge of the frame part f³ at each side of the machine, these pins passing up through the slots b⁴ of the plate b³, and where above the latter are provided with heads b⁶, that project over, so as to overlap the upper edges of the slots, and thus form guides for the longitudinal movement of the plates b³.

The letter b⁷ designates a set-screw, which

at each side of the machine revolves loosely in the upturned end b⁸ of the frame-extension f³ and is threaded into the upturned end b⁹ of the plate b³, so that said set-screws can be operated to draw out rearwardly the bearing-boxes of and the roller R⁴ when it is desired to put more tension upon the belt running thereon.

The letter B' designates an endless conveying-belt that is adapted to run on the roller R' over the top of the roller R² to the roller R⁴ to make its return stretch by passing around the latter roller, to pass down over the roller R³ beneath the roller R², back to the roller R', as shown at Fig. 5. The function and operation of this belt will be described subsequently.

The letter B² designates another endless conveying-belt that is adapted to run under the rollers N' and N² on its lower and rearward stretch to pass around the roller N³, to make its return stretch over the roller N² to the roller N⁴ to descend to the roller N', as shown at Fig. 5. These belts as operated move with the lower stretch of the upper belt B² in contact with the upper stretch of the lower belt B', and where thus in contact move rearwardly. The belt-roller N' has bearings for its journals at n² each side of the machine. The belt-roller N² has journals in bearing-boxes n³ at each side of the machine, each of which bearings is adjustable in a vertical slideway n⁴ to be operated upon by a pivoted lever n⁵, having a downward-extending arm n⁶, that rests on the bearing-boxes at each side of the machine, and with said lever at its outer end provided with a weight n⁷. The belt-roller N³ has bearings for its journals in the frame sides at h⁹. The bearings of the roller N⁴ are made longitudinally adjustable in the upwardly-extending frame parts f⁴ by the following mechanism:

The letter i³ designates a horizontal slide-way that is constructed on the inner face of each of the frame parts f⁴, and i² a slide-plate adapted to move in each of said slide-ways. On the inner end of each slide-plate one of the journals i' of the roller N⁴ is held.

The letter l⁴ designates an ear that is projected from the inner side of each of the slide-plates i², and the letter i⁵ designates an ear that is projected inwardly from each of the frame parts f⁴, and the letter i⁶ designates a set-screw, which at each side of the machine extends through the ear i⁵ of each of the frame parts f⁴, but not threaded therein, and which set-screw, beyond where passing through the ear i⁵ is threaded into the ear i⁴ of each of the said slide-plates, with a collar formed on each of the set-screws at i⁷ where outside of the ear of the frame part f⁴, and which bears on the latter when operated to draw out the slides, their bearings, and the roller N⁴ for the purposes of increasing the tension of the belt running on said roller.

The letter I designates two vertically-arranged oscillating bars, of which there is one

at each side of the machine. Each of these bars I at its lower end connects with a horizontal rock-shaft S, the latter having its bearings in the frame F at y.

5 The letter B³ designates another bar that is horizontally arranged between and connected to each of the oscillating bars I to move with them. Each of these oscillating bars I is made with a cross-head H, having constructed there-
10 in a vertical slide h³, and the letter h⁴ designates a slide-block arranged in each of said slides, and the letter j designates a journal-bearing formed in each of said slide-blocks, the function of which will be explained hereinafter.

The letter B⁴ designates a pitman, which at its inner end is journaled onto the bar B³ and at its other end is connected with a crank K, formed in the main driving-shaft S⁴. This 20 main driving-shaft has its bearings in the frame F, and where projecting through and beyond the latter, as shown at Fig. 4, it has two fast pulleys thereon, besides a loose pulley, the fast pulleys being indicated at P² and P³ and the loose pulley at P⁴, the pulley P³ being adapted to receive power from a driving-belt. (Not shown.)

The letter B⁵ designates a connecting-rod that on its inner end is journaled onto the 30 cross-bar B³ and at its outer end connects at v² with a crank K⁴ on the rock-shaft S⁸. The letter V designates a crank-arm arranged on and keyed to said rock-shaft S⁸ outside the frame F, as shown at Fig. 1.

35 The letter v⁵ designates a connecting-rod, which at its lower end is pivotally connected with the crank-arm V at v⁴ and at its upper end v⁶ connects with a bell-crank lever v⁷, that is pivoted on the shaft S⁵ of the lower feed-40 roller w², so as to turn thereon, and the upper arm of this bell-crank lever is constructed with a pawl v¹⁰, that operates a ratchet-wheel K², that is secured to said shaft S⁵. The letter G² designates a gear-wheel on the latter 45 shaft inside of said ratchet-wheel, and this gear-wheel meshes into a gear-wheel G³ on the shaft S¹⁶ of the upper feed-roller w'. As thus constructed and arranged when the bars I oscillate they operate the rock-shaft S⁸ by 50 means of the connection specified, and by means of the crank-arm V on said rock-shaft and the connection between the crank-arm and the ratchet-wheel K², the feed-rollers w' and w² are actuated to move with intermittent 55 periods of motion and alternating periods of rest by and through their geared connection G² and G³, and to move at their peripheries at each reciprocation of the bar I about half the distance made by the conveying- 60 belts B' and B² at each intermittent movement made by the said belts.

While for most uses I prefer to operate the feeding-rollers with an intermittent rotation, yet for some kinds of work they may be operated continuously, provided their surfaces run at a slower rate of speed than the conveying-belts which carry the articles into the

starching-trough, so that the articles being supplied to the machine when caught by the more rapidly moving belts will be pulled upon 7c and straightened out before passing under the operation of the starching-rollers. When the feed-rollers are thus moved continuously, they are operated by a modification of the mechanism as shown at Fig. 9, in which B⁷ 75 is a belt receiving power from the continuously-moving driving-shaft, (not shown in this figure,) and P⁷ and P⁶ pulleys arranged on the pintle-shaft S⁹, projected from the frame F.

The letter P⁵ designates a pulley on the 80 shaft S¹⁶ of the upper feed-roller w', and B⁸ a belt running on the pulleys P⁶ and P⁵, with the pulley P⁶ of a size sufficient to reduce the speed of the shaft S¹⁶ sufficiently to have it rotate the feed-rollers with less surface speed 85 than the movement of the belts B' and B², with the gear G³ of the upper feed-roller w' meshing into the gear-wheel G² of the lower feed-roller w² to move the latter.

The letter D designates a disk-wheel ar- 90 ranged on the driving-shaft S⁴ on that end of the latter which is opposite to that on which the driving-pulley is placed and where this shaft passes through to project beyond the frame F, as shown at Figs. 2 and 4.

The letter d² designates a connecting-rod that at d³ is pivoted to the outer face of the disk-wheel D, away from its center, as shown at Fig. 2.

The letter d⁴ designates a bell-crank lever 100 that where its angular arms meet is pivoted to so as to turn on the shaft S⁶ of the belt-roller R². The arm d⁵ of the bell-crank lever is pivotally connected with the connecting-rod d² at d⁶. To the upper arm d⁷ of the bell-crank lever d⁴ there is pivoted a pawl d⁸, and the letter d⁹ designates a ratchet-wheel ar- 105 ranged on and secured to the shaft S⁶ of the belt-roller R².

The letter G⁴ designates a gear-wheel se- 110 cured to and arranged on the shaft S⁶, and G⁵ a gear-wheel arranged on and secured to the shaft S⁷ of the roller N², which last-named gear-wheel meshes into the gear-wheel G⁴ to receive power therefrom. The letter G⁶ des- 115 ignates a gear-wheel that is also arranged on and secured to said shaft S⁶, and this gear-wheel G⁶ meshes into a gear-wheel G⁷ on the shaft g⁸ of the belt-roller N³, and the letter G⁸ designates a gear-wheel on the shaft of the 120 roller R³, which last-named gear-wheel meshes into the gear-wheel G⁴ to receive power therefrom. By means of this connection, made with the disk-wheel D and the bell-crank le- 125 ver d⁴, its pawl, the ratchet-wheel on the shaft S⁶, and the before-named gear-wheels thereon, which mesh into gear-wheels on the shafts of the rollers N², N³, and R³, these belt-rollers are operated to give to the belts B' and B² intermittent motion.

The letter D² designates a disk-wheel ar- 130 ranged between the ratchet-wheel d⁹ and the train of gears, including gears G⁵ and G⁸.

The letter u designates a belt adapted to

run on and to receive power from the main driving-shaft S^4 and the pulley P^2 thereon, and to also run upon the pulley p^5 , arranged on the shaft p^6 of the rubbing-roller r^3 , and the letter g^4 designates a gear-wheel arranged on said shaft p^6 back of said pulley, and which last-named gear-wheel meshes into another gear-wheel g^5 on the shaft g^6 of the other rubbing-roller r^4 to thus communicate continuous motion in opposite directions to the rubbing-rollers, the function of which will be described hereinafter.

The letters C' designate two starching-roller carriers, of which there is one at each side of the machine, and each of these carriers C' is provided with a journal j^2 , arranged to project from and at right angles to the outer side of the said carrier, each of said journals being adapted to turn in one of the sliding blocks h^4 of the cross-heads H of the oscillating bars I , as shown at Figs. 1, 2, and 6.

The letters A^2 A^2 designate two starching-rollers, each of which has a journal y^3 at its ends extending outwardly from the roller, so that when the carriers C' are passed down over the roller-journals the latter will have a bearing in the inverted- U or semi-tube form bearings y^3 of the said carriers at each side of the machine. By this construction and arrangement of the starching-rollers A^2 A^2 when the bars I at their upper ends are oscillated the carriers C' and the starching-rollers A^2 are reciprocatingly moved over the lower stretch of the upper conveying-belt B^2 where in contact with the upper stretch of the lower conveying-belt B' .

The letter M designates a cover placed between and connected to each of the carriers C' at their sides near their tops. When the carriers are being thus reciprocated by the oscillation of the bars I , the slide-blocks h^4 , in which the said carriers are journaled, move in the vertical slides formed in the cross-heads H at each side of the machine.

The letters O O designate another pair of starching-rollers that are located in the trough T in front of the rollers A^2 . These rollers O O are provided with carriers C^2 , each of which is made like the carriers C' , before described, with the exception that instead of being journaled in the slide-blocks of the cross-heads H of the bars I each of these carriers C^2 , as located at opposite sides of the machine, is made to pivotally connect with one of the cross-heads H to receive reciprocating motion therefrom by means of a link L at each side of the machine, one end of these links connecting pivotally at l^3 to the carrier C^2 and at the other end at l^6 with the cross-head H . Each of these carriers C^2 is provided with semi-tube or inverted- U form bearings U , which are placed over the journals c^2 of the rollers O .

The letter M^2 designates covers that are placed over the carriers C^2 to connect the latter. As thus placed, when the carriers C' are reciprocated the carriers C^2 are also recipro-

catingly moved over the lower stretch of the upper belt B^2 , with the rollers O O running thereon.

The letters C^3 designate two other carriers that are made like the carriers C^2 , with the exception that they have bearings for three rollers instead of two, there being one of these carriers arranged at each side of the machine connected by an intermediate cover M^3 . Each of these carriers C^3 is furnished with semi-tube or inverted- U form bearings U to receive the journals c^3 of the starching-rollers J J J . These latter starching-rollers rest upon the lower stretch of the upper conveying-belt B^2 . The carriers C^3 are each connected by means of a link L^2 with the cross-head H at each side of the machine to receive reciprocating motion therefrom. Each of these links L^2 connect at l^5 pivotally with one of the cross-heads H and at l^8 to a carrier C^3 .

The rollers N^4 and N^3 have an exterior covering of rubber, which is indicated at z of the sectional illustration of the roller N^4 , (shown at Fig. 8,) and in which respects the rollers N^3 and N^4 are alike. This rubber covering is ribbed or fluted circumferentially, as shown at r^9 of said Fig. 8, and the object of so making the rubber covering is to prevent the belt B^2 from working off the ends of the roller, said belt being made of loosely-woven material, as before described.

By means of the set-screws a^8 in the arms A , in which the bearings of the roller R' are placed, as these arms are moved outwardly and rearwardly the roller R' is also moved rearwardly, which increases the tension on the belt B' . The roller r^3 runs with its surface moving in a direction opposite to that of the belt B' , so as to be in contact with the upper stretch of the latter and articles adhering to the upper surface thereof, and the roller r^4 runs with its surface moving in the same direction as the belt B' , but faster than the latter and in contact with the upper stretch thereof and articles adhering thereto. As thus constructed, as articles passing from the starching-rollers and adhering to the upper surface of the belt B' come under the action of the rollers r^3 and r^4 they are rubbed by these rollers and straightened out, if wrinkled or folded, by being rubbed in opposite directions by said rollers and any surplus starch thereon is removed. By means of the set-screws b^7 in the upturned ends of the frame part f^3 the tension of the belt B' on the roller R^4 is increased. By means of the set-screws i^6 the tension of the belt B^2 is increased.

The operation of the apparatus thus illustrated and described is as follows: Hot starch having a proper condition of fluidity being supplied to the trough T , the pulley of the driving-shaft is put in motion and the bars I are actuated to oscillate and reciprocatingly move the carriers C' , C^2 , and C^3 and their starching-rollers over the upper surface of

the lower stretch of the upper belt B^2 where moving in the same direction and resting upon the upper stretch of the lower belt B' on the platform P , said belts being operated, as before described, with intermittent periods of motion. Articles to be starched are entered between the feeding-rollers moving slower than the said belts. The articles as thus entered are caught by the two 5 belts, so as to be between them, and are pulled upon by the latter moving faster than the feed-rollers, which pulls upon the articles to stretch them out and straighten them before descending with the belts into the starch. While being moved rearwardly the articles between the conveying-belts are operated upon by the starching-rollers passing over the lower stretch of the loosely-woven upper belt to fill them with starch by repeated 10 movements of said starching-rollers, from which operation the articles adhering to the upper surface of the upper stretch of the lower belt are passed under the influence of the rubbing-rollers to be taken from the extension m of the belt B' by the operator. The rubbing-rollers, moving in opposite directions, as before described, smooth out the articles, and by their opposite motion, where moving at their bottom surfaces, rub from them any 15 surplus starch, the roller nearest the front end of the machine having its under surface running in the opposite direction to the belt B' and the other running with its under surface moving in an opposite direction. The 20 carriers C' , with their starching-rollers A^2 , the carriers C^2 , with their starching-rollers O , the carriers C^3 , with their starching-rollers J , constructed and connected to be operated by the oscillating bars I , as shown and described 25 30 35 40 45

herein, are substantially the same in construction and arrangement as are shown in said older application before alluded to. The general construction and function of the starching-trough and its platform are also substantially the same as shown in my older application alluded to.

While I have illustrated and described the feed-rollers w' and w^2 as used in connection with conveying-belts moving faster than the 50 said rollers, the function of the rollers thus moved relatively to the more rapid movement of the belts would be the same as regards straightening out the articles to be starched, whether the said belts moved continuously or 55 intermittently. Hence I do not limit my combination of the feed-rollers actuated to move slower than the conveying-belts to the use of the latter so moved intermittently.

Having thus described my invention, what 60 I claim, and desire to secure by Letters Patent, is—

1. The combination, with a starching-machine constructed with a starch-trough and having two conveying-belts operated to run 65 therein, with the lower stretch of the upper belt in surface contact with the upper stretch

of the lower belt when both belts are moving rearwardly, of starching-rollers constructed and operated to be moved back and forth and reciprocatingly rotated over the lower stretch 70 of the upper belt, and a rearward extension of said lower belt beyond where the upper belt separates therefrom to make its return stretch, substantially in the manner as and for the purposes set forth. 75

2. The combination, with a starching-machine constructed with a starch-trough and having two endless conveying-belts operated to run therein, with the lower stretch of the upper belt in surface contact with the upper 80 stretch of the lower belt, and starching-rollers operated to move over said belts, substantially as described, of two feed-rollers actuated to rotate with the surface of the rollers moving at a slower speed than the belts, substantially as and for the purposes set forth. 85

3. The combination, with a starching-machine constructed with a starch-trough and having two endless conveying-belts operated to run therein, with the lower stretch of the 90 upper belt in surface contact with the upper stretch of the lower belt when moving rearwardly, of a rearward extension of said lower belt beyond where the upper belt separates from the lower belt to make its return stretch, 95 and two rubbing-rollers, side by side, arranged to engage with the upper stretch of said rearward belt-extension, with one of said rollers actuated to turn with its lower surface moving in the same direction as the upper stretch 100 of the belt-extension and the other one of said rollers having its bottom surface running in an opposite direction, substantially in the manner as and for the purposes set forth. 105

4. The combination, with a starching-machine constructed with a starch-trough and having two conveying-belts operated to run upon rollers, with the lower stretch of the upper belt in surface contact with the upper stretch of the lower belt when moving rearwardly, of starching-rollers constructed and operated to be moved back and forth and reciprocatingly rotated over the lower stretch 110 of the upper belt in contact therewith and a rearward extension of said lower belt beyond 115 where the upper belt separates therefrom to make its return stretch, with the roller on which said rearward extension of the lower belt runs to make its return stretch having its bearings in a slide-plate made with a guide-slot and a guide-pin and connected with a set-screw in the machine-frame extension and arranged to be operated substantially in the manner as and for the purposes set forth. 120

Signed at Troy, New York, this 10th day of 125 July, 1891, and in the presence of the two witnesses whose names are hereto written.

JOSEPH MCKAY.
